UNITED STATES PATENT OFFICE.

EDWARD H. SCHWAB, OF SOUTH BETHLEHEM, PENNSYLVANIA.

SPARK-PLUG.

1,359,437.

Specification of Letters Patent. Patented Nov. 16, 1920.

Application filed March 3, 1919. Serial No. 280,339.

To all whom it may concern:

Be it known that I, EDWARD H. SCHWAB, a citizen of the United States, residing at South Bethlehem, in the county of Northampton and State of Pennsylvania, have made certain new and useful Improvements in Spark-Plugs; and I do hereby declare the following to be a full, clear, and exact description of the invention, such as will enable others skilled in the art to which it appertains to make and use the same, reference being had to the accompanying drawings, and to the figures of reference marked thereon, which form a part of this specification.

This invention relates to spark-plugs for internal combustion engines, and has for its object to provide a composite insulation for spark-plugs in which porcelain and mica are employed.

A further object of the invention is to provide a spark-plug having an insulation of porcelain and mica, in which a novel construction is employed for mounting the porcelain and mica members of the insulation on the electrode spindle.

With these and other objects in view, the invention consists of the novel construction of the electrode spindle; in the novel construction of mounting the porcelain and mica members of the insulation, and in certain details of construction and combinations of parts, all of which will be first fully described and afterward specifically pointed out in the appended claims.

Referring to the accompanying drawing:

The figure is a vertical sectional view of a spark-plug constructed in accordance with this invention.

Referring to the drawing by reference numerals:

1 indicates the spark-plug having a metal shell 2, threaded at 3 for connection with a motor, and formed preferably hexagonal at 4 to receive a suitable wrench. The shell 2 is internally chambered to receive the insulation and is provided with an internal seat or shoulder 5 and has a female threaded portion 6 to receive the male threaded portion 7 of the gland or bushing 9, said gland or bushing 8 being shouldered at 10 for engagement with the porcelain member of the insulation, as will be presently described.

Referring now to the insulation 11, it will be seen that the same includes an inner

porcelain member 12, and an outer mica member 13. The porcelain member 12 is provided exteriorly with a shoulder 14 complementary to the shoulder 5 in the shell, and is internally bored to receive the electrode-spindle 15. As shown this bore is preferably of three diameters the lowermost and smallest diameter 16 receiving the electrode-rod 17, while the central and intermediate 18 is provided with a female thread 19 to receive the male threaded portion 20 of the electrode spindle 15, a shoulder 21 being formed at the juncture of the said central or intermediate diameter 18 of the bore and the uppermost and largest diameter 22.

The electrode spindle 15 receives the electrode rod 17, and directly above the threaded portion thereof, is a flange or shoulder 23 complementary to the shoulder 21 in the porcelain insulating member. A similar flange or shoulder 24 is formed on the spindle 15 near the head thereof, between which shoulders 23 and 24, a wrapping 25 of mica 25 is positioned, as shown in the drawing. The outer end of the spindle 15 is threaded at 26 to receive a suitable terminal head 27, while a flange 28 is formed on the spindle directly under the said threaded portion 26 thereof.

The insulation is assembled as follows:

A suitable gasket 29 is passed on the spindle 15 and against the flange 28 thereof; the mica wrapping 25 is applied between the flanges 23 and 24, and the mica washers which form the mica section 13 are then passed on the spindle and over and around the mica wrapping 25. The spindle 15 is then threaded into the porcelain member 12, a suitable cement being employed at the threaded portion thereof, and said spindle 15 is progressed into the porcelain member 12 until the flange or shoulder 23 thereof is seated firmly on the complementary shoulder 21 in the porcelain. This threading of the spindle 15 into the porcelain member 12 carries the mica section 13 down upon the flat face 30 of the porcelain member 12, and tightly compresses the mica washers 31 thereof between said porcelain member 12 and the uppermost flange 28 and gasket 29 on the spindle 15, in such manner that a strong, rigid, permanent and gas tight structure is assured. The washers forming the mica section 13 can then be machined to form and size.

In assembling the insulation in the shell, a suitable soft gasket 31 is disposed on the seat or shoulder 5 to provide a gas-tight joint between the insulation and the shell.

5 After the insulation is inserted, a suitable gasket 32 is placed on the top of the porcelain member 12, and the gland or bushing 9 is threaded into the shell with pressure sufficient to effectively seat the porcelain member 12 on its gasket 31.

10 A ground electrode of any approved type is provided, as for instance, a transverse rod 33, having both ends embedded in the shell, and spaced from the central electrode rod 11 to provide a suitable spark-gap.

15 The advantages flowing from the foregoing construction will be at once apparent to those skilled in the art, as in a simple and inexpensive manner, a particularly durable 20 and efficient plug is provided; one in which the tendency of the porcelain to fracture is reduced to the minimum, and in which the mica components are remote from the injurious action of oil and the direct, intense heat 25 of the flame in the motor.

Having thus fully described the invention, I wish it to be understood that while the construction shown in the drawing and described in this specification discloses the 30 preferred embodiment of this invention, nevertheless the same is susceptible of changes and modifications in the construction and arrangement of the parts, and that I consider myself clearly entitled to all such 35 changes and modifications as fall within the limit and scope of the appended claims.

What I claim as new and desire to secure by Letters Patent of the United States, is:

1. A spark-plug including a metal shell 40 and gland, an insulation including an inner porcelain member and an outer mica member, the porcelain member being internally threaded, an electrode spindle passed through said mica member and having a 45 threaded portion for threaded connection with the porcelain member, the spindle including means for retaining the mica section thereon, and a wrapping of mica encompassing said spindle and positioned 50 within the porcelain and mica members.

2. A spark-plug including a metal shell, an insulation including an inner porcelain

member and an outer mica member, the porcelain member being internally threaded, an electrode spindle passed through the 55 mica section and including means at its terminal end for retaining the mica section thereon, said spindle including a threaded portion for threaded connection with the porcelain member to compress the mica 60 member upon the porcelain member, and a wrapping of mica around the electrode spindle and within both the porcelain and mica members.

3. A spark-plug including a metal shell, 65 an insulation including an inner porcelain member and an outer mica member, the porcelain member being internally threaded, an electrode spindle passed through the mica section and including means at its 70 terminal end for retaining the mica section thereon, said spindle including a threaded portion for threaded connection with the porcelain member to compress the mica member upon the porcelain member. 75

4. A spark-plug including a metal shell, a gland for threaded connection therewith, an insulation including a porcelain member having a flat face to be engaged by said gland, and including a mica section, said 80 porcelain section being internally threaded, an electrode spindle upon which the mica section is mounted and including means at its terminal end for retaining the mica section thereon, and including a threaded portion 85 for threaded connection with the porcelain member to compress the mica section upon the said flat face of the porcelain section.

5. A spark-plug including a metal shell, 90 an insulation including a porcelain member and a mica member, the plug including means for exerting pressure on the porcelain member to retain same within the shell, said porcelain member being internally 95 threaded, an electrode spindle including a threaded portion upon which spindle the mica section is mounted, the said threaded portion of the spindle being threaded into the porcelain member and compressing the 100 mica member upon the porcelain member.

In testimony whereof, I affix my signature.

EDWARD H. SCHWAB.
